UNITED STATES PATENT OFFICE.

HORACE WYMAN, OF WORCESTER, MASSACHUSETTS.

FIRE-EXTINGUISHING APPARATUS.

SPECIFICATION forming part of Letters Patent No. 392,250, dated November 6, 1888.

Application filed February 2, 1885. Serial No. 154,642. (No model.)

To all whom it may concern:

Be it known that I, HORACE WYMAN, of the city and county of Worcester, State of Massachusetts, have invented an Improvement in 5 Fire-Extinguishing Apparatus, of which the following description, in connection with the accompanying drawing, is a specification, like letters on the drawing representing like parts.

My invention relates to a fire-extinguishing 10 apparatus of that kind which forms a permanent part of the building or structure to be protected, the water or fire-extinguishing material being automatically discharged or permitted to flow when a fire takes place by the 15 action of material sensitive to changes in temperature, usually by the melting of material or solder fusible at a low temperature.

The invention is embodied in apparatus of 20 that class in which the water employed for extinguishing the fire is normally kept excluded from distributing-pipes in the building by a main valve, which is permitted to open upon the breaking or opening of one of the sprinklers or fusible plugs by a rise in temperature.

25 In my invention the main water-valve is normally held upon its seat by the unbalanced pressure of the air at one side of a piston connected with the main water-valve, so that a given air-pressure on the said piston is able 30 to overcome and restrain a greater water-pressure for the same area on the water-valve, which is normally kept seated against the pressure of the water in the main or supplying pipe. The unbalanced air-pressure is shown 35 as produced by exhausting the air from the water-distributing pipes, or an independent set of air-pipes in proximity thereto, thus leaving the unbalanced atmospheric pressure external to the apparatus acting on the piston, 40 which preferably has a larger area acted on by the air than the area of the main valve exposed to the pressure of the water, and is connected with the said main water-valve by a lever which gives mechanical advantage to the 45 piston acted upon by the atmospheric pressure.

Apparatus has been previously made in 50 which a main valve has been held seated by the pressure of air within the pipes, instead of by the external atmospheric pressure; but in 55 practice it is very difficult to maintain the internal pressure for any considerable length of time, as it is very difficult to discover the

minute leaks through which the air escapes, or to stop from the outside of the pipes the leaks through which the air escapes from the 55 inside of the pipes. I have discovered that this objection may be almost, if not entirely, overcome by maintaining the valve seated by the atmospheric pressure while the air is rarefied in the pipes, for in this plan the leaks of the 60 pipes may be easily stopped by the application of paint or a similar covering to the outside of the pipes, in which case the external pressure of the air tends to force the paint or similar material into the leaks, tightly closing 65 them wherever they may be. As it is, however, almost impossible to maintain an absolutely-uniform pressure in the pipes or other confined spaces differing materially from the pressure external to the said pipes for an indefinite 70 period of time, the apparatus is provided with an air-pump, which may be automatically operated by a motor actuated by the water in the main pipe to maintain the pressure substantially uniform in the pipes. 75

This system may be designated a "vacuum" system, that being its principle of operation. In my application, Serial No. 157,472, filed March 2, 1885, I have set forth an air-pressure system. 80

The drawing shows, mainly in vertical section, a fire-extinguishing apparatus embodying this invention, the water-distributing and air pipes being shown in elevation.

The main pipe *a*, containing water under 85 pressure, enters a valve apparatus, *A*, consisting of a chamber, *b*, communicating with the main or inlet pipe *a*, and a chamber, *c*, communicating with the distributing-pipes *B*, provided with suitable distributing or sprinkling 90 devices, *d*, normally kept sealed or closed by a material sensitive to changes in temperature—such, for instance, as solder fusible at a low temperature, slightly above the highest natural temperature of the atmosphere. 95

The water is normally kept from passing from the chamber *b* to the chamber *c* and distributing-pipes by the main water-valve *e*, consisting of a piston or disk on a stem, *f*, which piston is normally seated upon a shoulder or seat, *b'*, against the pressure of water in the chamber *b*. The stem *f* passes through a cylindrical neck, *b''*, from the chamber *b* into the external atmosphere, being either provided

with a suitable stuffing-box or packing, or preferably, as shown, with a piston, b^3 , fitting in the neck b^2 and tightly closing the same, the pressure of the water on the said piston 5 partly balancing that on the piston e , tending to open the valve, although the said piston e is enough larger than the one b^3 to enable the water to open the valve except when prevented by other means. The said stem f is 10 connected by link f' with the short arm of the lever g , having its long arm connected with a piston, h , fitting air-tight within the cylinder i , and exposed to unequal air-pressure on its opposite sides, being shown, in this instance, 15 as receiving the atmospheric pressure on its upper side and acted upon by a lower pressure or partial vacuum at its under side.

The space in the cylinder i below the piston h is preferably connected with a series of air-pipes, k , which may be of small diameter and are provided with orifices k' , normally closed or sealed by sensitive material and placed in proximity to the distributors d , so that a rise in temperature which would cause the opening 25 of one of the distributors would also cause the opening of the adjacent orifices k' , admitting air to the pipe k , thus destroying the vacuum in the cylinder i below the piston h , so that the pressure on both sides of the latter would be 30 balanced and would no longer tend to hold the valve e to its seat.

By giving the piston h greater leverage than the valve-stem f , and also by making the said piston h of greater area than the one e , or 35 greater than the difference between the one e and the one b^3 , a comparatively slight pressure on the upper side of the piston h is sufficient to retain the valve e seated against a far greater pressure per square inch in the main pipe a .

40 The vacuum-chamber in the cylinder i below the piston h may be connected with the distributing-pipes B , and the vacuum maintained in the latter, instead of in the pipe k , which pipe k might in this construction be 45 omitted, the vacuum being destroyed by the opening or unsealing of one of the distributors d , or other orifices, d' , adjacent thereto. The cylinder i is shown as connected with the distributing-pipes B by a pipe, m , provided with 50 a cock, n , so that communication may be cut off or established between the cylinder i and pipes B , as may be desired. As shown in this instance, the valve-stem f is provided with a large piston, o , fitting within a cylinder, o' , 55 below the outlet-chamber e of the valve, the said piston and cylinder serving partly as a guide for the valve-rod in its movement, and also operating, in case the distributing-pipe B and chamber e constitute a portion of the 60 vacuum-space, as described, to retain the valve e on its seat, the said piston o being exposed to the atmospheric pressure at its under side, and being of greater area than the piston b^3 , which is exposed to atmospheric pressure in 65 the opposite direction.

As it is very difficult, if not impossible, to make piping perfectly tight, the air-pump

p , which is employed to remove the air from the cylinder i below the piston h and the connected piping, is preferably connected with a 70 motor, p' , which may be, for instance, such as shown in Letters Patent No. 144,747, dated November 18, 1873, or of any suitable construction operated by the water in the pipe a passing to the said motor through a branch 75 pipe, p^2 , the relative areas of the pistons in the motor p' and pump p , or the mechanical connection between the said pistons, being such that the pressure of the water in the pipe a on the piston of the motor will be balanced by 80 the air-pressure on the piston of the pump when the desired difference in air-pressure on the opposite sides of the piston h has been produced.

In this my invention, by simply exhausting 85 or rarefying the air in a chamber provided with a movable partition or diaphragm exposed on one of its sides to the pressure of the atmosphere, and by connecting this diaphragm to the stop-valve, I am enabled to utilize this 90 direct pressure of the atmosphere to hold the valve closed. The equalizing of the pressure in the chamber to that of the atmosphere will remove this pressure from the valve and permit the pressure of the water in the supply- 95 pipe to open the valve and flow to the distributing or sprinkler pipes. I am thus enabled by the direct pressure of the atmosphere, and entirely without other holding mechanism or without the employment of mechanical devices, to retain the stop-valve closed, or to open it by removing that pressure.

I claim—

1. In a fire-extinguishing apparatus, the combination, with an air-chamber provided 105 with a movable partition or head, and having an internal pressure different from that of the atmosphere, and with a connected pipe provided with a closed aperture or apertures fitted to open by a rise of temperature of the surrounding atmosphere, of a water-supply pipe 110 provided with a stop-valve held to its seat by the normal pressure of the air-chamber acting on the movable partition, whereby when the air-pressure in said chamber is restored to that 115 of the atmosphere the pressure will be removed from the said valve, and the pressure of the water in the supply-pipe will open the said valve and admit water from the supply-pipe to the discharge or sprinkler pipe for the extinction of fires, substantially as described.

2. In an automatic fire-extinguishing apparatus, a main supply-pipe and distributing-pipes, and a main valve controlling the flow of water from the former to the latter, and air-pipes governing by changes in pressure therein the operation of the main valve, and an air-pump and motor therefor automatically operated by the water in the main pipe below the main valve, whereby the pressure is maintained substantially uniform in said pipes while in their normally-sealed condition, substantially as set forth.

3. The combination of the main and dis-

tributing water-pipes *a* and *B*, respectively, the valve *e*, seated in a chamber between the said pipes and against the pressure of the water in pipe *a*, the valve-stem *f*, the piston *h*, 5 and the lever *g*, connecting the stem *f* and piston, and the chamber *i*, containing the piston and opening normally to the external atmosphere above the piston, substantially as described.

10 4. An air-chamber provided with a movable piston and connected pipe with closed apertures therein containing an air-pressure different from that of the atmosphere, combined with a water-supply pipe and a discharge or sprinkler pipe with a stop-valve between them, and a connection between said valve and air-chamber piston, whereby the atmospheric pressure produced upon said valve by the said difference in pressure acts to hold 15 the stop-valve closed and exclude the water from the sprinkler-pipe, substantially as described.

20 5. A stop-valve with a head to prevent the passage of water, its spindle, and an additional head to receive a counteracting pressure from 25

the water, combined with a chamber having an internal pressure different from that of the atmosphere, and provided with a movable piston with one side exposed to the pressure of the atmosphere, a connected pipe with closed apertures fitted to open by a rise in temperature of the surrounding atmosphere, and a connection from said piston to said valve to act with the additional counteracting head with an excess of pressure to hold said valve 30 closed, whereby upon a rise of temperature in the surrounding atmosphere sufficient to open the closed apertures the excess of pressure upon said valve will be removed and the water-pressure will act upon the valve and permit 35 the water to flow to the sprinkler-pipes, substantially as described.

In testimony whereof I have signed my name to this specification in the presence of two subscribing witnesses.

HORACE WYMAN.
